Primary Examiner — T. Chase Nelson*Assistant Examiner* — Mark Cavanna*(74) Attorney, Agent, or Firm* — Harness, Dickey & Pierce, PLC**CLAIM**

The ornamental design for a toothbrush training device, as shown and described.

DESCRIPTION

FIG. 1 is a front view of a toothbrush training device showing my new design,

FIG. 2 is a side view thereof;

FIG. 3 is a rear view thereof;

FIG. 4 is an opposite side view thereof;

FIG. 5 is a top view thereof;

FIG. 6 is a bottom view thereof;

FIG. 7 is a perspective view of the toothbrush training device thereof shown in an open condition; and,

FIG. 8 is a perspective view of the toothbrush training device thereof shown in closed condition.

The broken line showing portions of the toothbrush training device form no part of the claimed design.
